UNITED STATES PATENT OFFICE

GEORGE F. HANDLEY, OF GLENDALE, NEW YORK, ASSIGNOR TO ROYAL TYPEWRITER COMPANY, INC., OF NEW YORK, N. Y., A CORPORATION OF NEW YORK

TYPEWRITING MACHINE

Application filed December 15, 1928. Serial No. 326,318.

This invention relates to improvements in typewriting machines generally and in machines of analogous arts, although more particularly to improvements in automatic ribbon reversing mechanisms such as is disclosed in my Patent 1,570,218, January 19, 1926.

In this patent construction, a button or other projection, which is located on the ribbon adjacent the unwinding end thereof, is moved by the ribbon into contact with an arm and the latter is thereby moved against the tension of a spring to effect the automatic operation of the ribbon reversing mechanism. Immediately following the completion of the reversing operation, the arm is returned by the spring to its normal or retracted position. The return movement of this arm, by reason of its contact with the button, causes that portion of the ribbon between the now active ribbon spool and the button to be formed into a loose loop-like formation or slack portion which must be taken up by the rotation of the spool before the ribbon begins its actual reverse feeding movement. The ribbon, where it is engaged by the type, remains stationary until said slack is taken up, and this failure of the ribbon to feed results in the ribbon being perforated by the type at this one spot.

It is, therefore, the principal object of the present invention to provide an automatic take-up mechanism for said ribbon loop or slack portion, which will function substantially instantaneously and immediately after the operation of the reversing mechanism, whereby the spool will immediately begin its feeding movement for the entire ribbon and the possibility of the type perforating the ribbon will be thereby avoided.

In the accompanying drawings:

Figure 1 is a front elevation showing an automatic ribbon reversing mechanism embodying my invention, the view showing the reversing mechanism in operation;

Figure 2 is a top plan view showing a part of the left hand ribbon spool, the ribbon, and the ribbon controlled arm which actuates the reversing mechanism;

Figure 3 is a horizontal section taken

below the right hand spool and showing the ribbon take-up mechanisms;

Figure 4 is a front elevation of a spool shaft, the upper portion of the lower section being in section;

Figure 5 is an end view partly in section showing the intermittent ribbon feeding means;

Figure 6 is a front elevation of the left hand spool shaft and associated ribbon take-up and reversing means, the view showing the reversing means in operative position and the ribbon controlled arm being in position to return to its initial position and form a slack portion in the ribbon;

Figure 7 is an enlarged sectional view showing the ratchet for turning the upper section of the spool shaft in ribbon feeding direction with the lower section;

Figure 8 is a side elevation of the right hand spool shaft showing a modified form of ribbon slack take-up means;

Figure 9 is a front elevation of the spool shaft shown in Figure 8;

Figure 10 is a plan view of the collar which is fixed to the upper end of the shaft shown in Figure 9; and

Figure 11 is a horizontal sectional view taken on the line 11-11 of Figure 9.

Referring to the drawings, the ribbon reversing mechanism shown therein is generally of the same construction as disclosed in the Handley Patent 1,570,218 referred to above, and therefore I have not shown a typewriting machine to which the ribbon reversing mechanism is applied.

This ribbon reversing mechanism comprises generally a pair of ribbon spools A, A which are respectively supported on vertical shafts B, B which in turn are each supported in offset arms 2 and 3 of a bracket 4 attached to the type bar segment. Fixed to the lower end of each spool shaft B is a bevel gear 5 with one of which meshes a bevel gear 6 at the right hand side of the machine and with the other of which meshes a similar bevel gear 7 at the other side of the machine, the gear 7 facing in opposite direction to the gear 6. The gears 6 and 7 are fixed to a driving shaft 8 which is journaled in downwardly extend-

ing arms 9 of the bracket 4. The shaft 8 is free to rotate in the arms 9 and may be moved longitudinally therein.

Near the right hand end, the shaft 8 has fixed thereon a large ratchet wheel 10 with fine teeth which are engaged by a pawl 11 pivotally connected at 12 to a universal bar 13 which is operated at each depression of the usual type key levers. A spring 14 yieldably retains the pawl 11 in engagement with the teeth of the ratchet wheel 10. During printing the pawl 11 will operate to rotate the shaft 8, which rotation will be transmitted to one or to the other of the ribbon spool shafts B, dependent upon which gear 6 or 7 is in mesh with its cooperative bevel gear 5.

Adjacent the bevel gear 6, the shaft 8 is provided with a fixed collar 15 having two grooves 16 and 17. A spring pressed detent 18 is pivotally connected to the bracket 4 and cooperates with the grooves 16 and 17 to hold the shaft 8 in either of its longitudinal or endwise adjustments, whereby either the gear 6 will be disposed in mesh with the gear 5, or the gear 7 will be disposed in mesh with the other gear 5. Thus, when the shaft 8 is automatically moved endwise to reverse the rotations of the spool shaft B, said shaft 8 will be retained by the detent 18 in its adjusted position. Fixed to the shaft 8, at each end thereof, is a special gear 19 and associated with each gear is a vertically movable pawl 20 having a tooth 21 adjacent its lower end. The upper end of the pawl 20 is provided with a longitudinal slot 22 through which a pin 23 extends, said pin being fixed to an arm 24 of the bracket 4, and the lower end of the pawl is guided in an opening formed in a horizontal plate 25 attached to the machine frame. Thus, the pawl 20 is guided for vertical movements relative to the associated gear 19. Consequently, when the pawl is raised and the tooth 21 is brought into engagement with the gear teeth, the rotation of the drive shaft 8 will cause a gear tooth to cam against the stationary tooth 21 of the pawl and thereby cause the shaft to move longitudinally, thereby coupling the gears 5 and 6 or 5 and 7 depending upon the direction of longitudinal movement of said shaft. Thus the ribbon spool A will be disconnected and the empty spool rotated in a direction to wind the ribbon thereon.

The reversing mechanism above described is duplicated at opposite sides of the machine but reversibly arranged in order that operation of the same will move the shaft 8 alternately in opposite directions.

The ribbon reversing mechanism is controlled and actuated by the ribbon C which is fed from one spool to the other, the ribbon passing through a ribbon vibrator D. The ribbon near each end is provided with a projection or button 27 which as ribbon is nearly fed from one spool, engages a ribbon guide

28, and moves the latter in a direction away from the spool. This guide 28 is fixed to one end of an arm 29 which is supported on an arm 30 of the bracket 4 for straight line movements in a horizontal plane through the medium of a pin and slot connection 31 between said arms. The opposite end of the arm 29 is pivotally connected as at 31 to the upper end of a vertical arm 32 of a three-armed lever 33 which is pivoted at its angle 70 as at 34 to the bracket arm 24. An arm 35 of said lever 33 is connected to the upper end of a coil spring 36, the lower end of said spring being connected to and yieldably supporting the pawl 20. The third arm 37 of said lever 33 is connected to the lower end of a coil spring 38, the upper end of the spring being connected to an ear 39 of the bracket 4. 75 80

Thus, when the button 27 is moved outwardly by the feeding action of the ribbon, it 85 engages the ribbon guide 28 and moves the arm 29 in a straight line which in turn rocks the three-arm lever 33 against the tension of the spring 38, and the arm 35 of said lever 33 through the medium of the spring 36 raises 90 the pawl 20 to engage the tooth 21 thereof with a tooth of the spiral gear 19 and thereby move the driving shaft 8 longitudinally to effect a coupling of the driving gears of the associated spool and an uncoupling of the 95 driving gears of the other spool. Simultaneously with the coupling of the gears, the spiral gear 19 becomes disconnected from the pawl 20, the spool shaft begins to rotate to feed the ribbon on the spool, and the spring 100 38 effects a quick return of the ribbon guide 28, arm 29, and lever 33 to their normal positions. The ribbon guide in its return movement pushes the button 27 and causes the formation of a loop or slack portion c in the 105 ribbon between the spool and the guide.

This slack or loop portion c must be taken up by the rotation of the spool before the main portion of the ribbon begins its feeding movement, because that portion of the 110 ribbon which is engaged by the type remains stationary until the slack above described has been taken up and as a result the continued striking of the type against the stationary part of the ribbon results in said ribbon being perforated by the type. 115

In order to automatically take up this slack in the ribbon substantially instantaneously and immediately following the operation of the reversing mechanism, I have provided the 120 following ribbon slack take-up mechanism.

In the form illustrated in Figures 1 to 7 inclusive, each spool shaft B is split intermediate its ends to form upper and lower sections 40 and 41 respectively, the upper 125 end of the lower section being provided with a seat 42 for receiving a reduced lower portion 43 extending downwardly from the lower end of the upper section 40. The lower portion of the upper section 40 is provided 130

on its periphery with a plurality of vertically disposed ratchet teeth 44. A collar 45 is fixed to the upper end of the lower section 41, and pivoted on the upper face of this 5 collar as at 46 is a pawl 47. The pawl 47 is provided with a nose 48 for engaging the ratchet teeth 44, and with a tail 49 which is engaged by one end of a flat spring 50 also attached to the upper face of the collar 45 10 and serving to yieldably retain the nose 48 of the pawl in engagement with said ratchet teeth. Thus, upon rotation of the lower section 41 of the shaft B, the pawl 47 will be rotated therewith, and, through the medium 15 of the nose 48 of said pawl engaging the ratchet teeth 44, the upper section 40 of said shaft will be rotated in the same direction as the lower section. The upper section 40, however, is capable of being rotated at a 20 greater speed and in the same direction as the lower section 41 by reason of the pawl 47 slipping over the ratchet teeth 44. A horizontally disposed spring arm 51 is pivotally connected at one end to the upper end of 25 the arm 32 of the lever 33 through the medium of the pivot 31, the other or free end of the arm 51 being mounted in an opening 52 formed in the ribbon guide arm 30. The arm 51 is provided with a plurality of laterally extending teeth 53 which, when the parts are in the position shown in Figures 1 and 6, are located in spaced relation to the ratchet teeth 44 of the spool shaft B. As 30 soon as the operation of the reversing mechanism has been completed, the ribbon guide 28 is returned to its normal position, as above stated, and consequently the arm 51 will be moved simultaneously with the ribbon guide and in the same direction. As a result, the 35 teeth 52 of the spring arm 51 will engage the ratchet teeth 44 of the spool shaft B and thereby rotate said upper section 40 in the same direction and faster than the rotation of the lower shaft section 41, thereby causing the spool to be rotated a sufficient distance and in the proper direction to take up the slack in the ribbon, which, as above described, is located between the spool and the ribbon guide. Both sections of the shaft 40 B will then rotate in unison to feed the entire ribbon.

In the modified form shown in Figures 8 to 11, the lower section 41 of the shaft B is provided below its upper end with a fixed 50 collar 54 having an upwardly extending drive finger 55 adapted to engage one or the other of spaced fingers 56 and 57 which are fixed to and depend from a collar 58 fixed to the lower end of the upper section 40 of said 55 shaft. A coil spring 59 surrounds the lower section 41 between the collars 54 and 58, and the upper end of said spring is fixed to the collar 58 and the lower end of said spring is fixed to the collar 54. Thus the upper section 60 65 40 of said shaft is adapted to be rotated in

either direction relative to the lower section 41, the spring 59 serving to normally retain the finger 56 in engagement with the stop finger 55 to thereby rotate the upper shaft section 40. Thus, upon rotation of the lower 70 shaft section 41 of one spool shaft in a clockwise direction, the upper shaft section 40 will be rotated in the same direction, whereas the lower section of the other spool shaft will be rotated in an anti-clockwise direction. 75

It is desirable to retain the lower section 41 of the spool shaft against rotation during the forward movement of the ribbon guide 28 so as to permit the ribbon during its feeding movement to rotate the upper section 80 40 of the shaft against the tension of the spring 59. I have, therefore, fixedly attached to the lower section 41 a collar 60 having a circular series of teeth 61 fixed to the upper end thereof. A pawl 62 is formed as an extension of the arm 37 of the lever 33 and functions to engage between a pair of teeth 61 when the ribbon guide 28 is moved to its limit under the influence of the ribbon button 27. Thus the lower section 41 of the 85 shaft is held against movement while the upper section 40 is being rotated under the influence of the ribbon feeding action. Consequently, as soon as the ribbon guide 28 begins its return movement due to the operation of the reversing mechanism, the spring 59 will reversibly rotate the upper section 40 of the shaft together with the ribbon spool until the finger 56 reengages the stop finger 55, and thereby quickly take up the slack 90 in the ribbon between the ribbon guide 28 and said spool. 95

From the foregoing, it will be observed that I have provided a ribbon reversing mechanism which is associated with each spool, 100 a ribbon controlled means for actuating the reversing mechanism; a means for returning the ribbon controlled means to its normal position immediately following the operation of the reversing mechanism whereby a 105 slack in the ribbon is formed between the spool and the ribbon controlled means, and also a means which is operable during the return movement of said ribbon controlled means for automatically and quickly taking 110 up the slack in the ribbon. 115

I claim:

1. In a typewriter or the like, a ribbon feeding mechanism, a ribbon reversing mechanism, a movable ribbon-controlled means for operating said reversing mechanism, means for returning the ribbon controlled means to its initial position immediately following the operation of the reversing mechanism whereby a slack in the ribbon is 120 formed, and means other than the ribbon feeding mechanism for automatically and substantially instantaneously taking up the slack in said ribbon immediately following the operation of the reversing mechanism. 125

2. In a typewriter or the like, a ribbon feeding mechanism, a ribbon reversing mechanism, a movable ribbon-controlled means for operating said reversing mechanism, means for returning the ribbon controlled means to its initial position immediately following the operation of the reversing mechanism whereby a slack in the ribbon is formed, and means operable during the return movement of the ribbon-controlled means for automatically taking up the slack in said ribbon.

3. In a typewriter or the like, a ribbon feeding mechanism including a spool, a ribbon reversing mechanism, a movable ribbon-controlled means including a projection on the ribbon and a ribbon guide movable by said projection in a direction away from said spool for operating said reversing mechanism, means for returning the ribbon controlled means to its initial position immediately following the operation of the reversing mechanism whereby a slack in the ribbon is formed between the spool and ribbon guide, and means other than the ribbon feeding mechanism for automatically and substantially instantaneously taking up the slack in said ribbon immediately following the operation of the reversing mechanism.

4. In a typewriter or the like, a ribbon feeding mechanism including a spool, a ribbon reversing mechanism, a movable ribbon-controlled means including a projection on the ribbon and a ribbon guide movable by said projection in a direction away from said spool for operating said reversing mechanism, means for returning the ribbon controlled means to its initial position immediately following the operation of the reversing mechanism whereby a slack in the ribbon is formed between the spool and ribbon guide, and means operable during the return movement of the ribbon-controlled means for automatically taking up the slack in said ribbon.

5. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, and a ribbon controlled means for operating said reversing mechanism, the upper shaft section being rotated in the same direction but faster than the lower section by the return movement of the ribbon controlled means immediately subsequent to the beginning of the operation of the reversing mechanism to take up the ribbon slack between the spool and the ribbon controlled means.

6. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, said upper shaft section being provided with a series of ratchet teeth, a ribbon-controlled means for operating said reversing mechanism, means for returning the ribbon-controlled means to its initial position whereby a slack in the ribbon is formed between the spool and the ribbon-controlled means, and means movable with the ribbon-controlled means and operable during the return movement of the latter to engage the ratchet teeth and thereby rotate the upper shaft section in the same direction as but at a faster speed than the lower shaft section to take up said ribbon slack.

7. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, said upper shaft section being provided with a series of ratchet teeth, a ribbon-controlled means for operating said reversing mechanism, means for returning the ribbon-controlled means to its initial position whereby a slack in the ribbon is formed between the spool and the ribbon-controlled means, a spring arm carried by said ribbon-controlled means, and a series of teeth fixed to said spring arm for engaging the ratchet teeth of the upper shaft section during the return movement of the ribbon-controlling means and thereby rotate the upper shaft section in the same direction as but at a faster speed than the lower shaft section to take up said ribbon slack.

8. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, said upper shaft section being provided with a series of ratchet teeth, a ribbon-controlled means for operating said reversing mechanism and including a button on the ribbon, a ribbon guide engageable by

the button, and a horizontally movable arm for supporting said guide, means for returning the ribbon-controlled means to its initial position whereby a slack in the ribbon is formed between the spool and the ribbon guide, and means carried by the horizontally movable arm of the ribbon-controlled means and operable during the return movement of the latter to engage the ratchet teeth and thereby rotate the upper shaft section in the same direction as but at a faster speed than the lower shaft section to take up said ribbon slack.

9. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, a ribbon-controlled means for operating said reversing mechanism, means for returning the ribbon-controlled means to its initial position whereby a slack in the ribbon is formed between the spool and the ribbon-controlled means, and means operable by the ribbon-controlled means during the return movement of the latter to rotate the upper shaft section in the same direction as the lower shaft section to take up said ribbon slack.

10. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, said upper shaft section being provided with a series of ratchet teeth, a ribbon-controlled means for operating said reversing mechanism, means for returning the ribbon-controlled means to its initial position whereby a slack in the ribbon is formed between the spool and the ribbon-controlled means, and means movable with the ribbon-controlled means and operable during the return movement of the latter to engage the ratchet teeth and thereby rotate the upper shaft section in the same direction as the lower shaft section to take up said ribbon slack.

11. In a typewriter or the like, a ribbon feeding mechanism, a ribbon reversing mechanism, a movable ribbon-controlled means for operating said reversing mechanism, a spring for returning the ribbon controlled means to its initial position immediately following the operation of the reversing mecha-

nism whereby a slack in the ribbon is formed, and means operable by and during the return movement of the ribbon-controlled means for automatically taking up the slack in said ribbon.

12. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, and a ribbon controlled means for operating said reversing mechanism and including a return spring, the upper shaft section being rotated in the same direction but faster than the lower section by the return spring during the return movement of the ribbon controlled means immediately subsequent to the beginning of the operation of the reversing mechanism to take up the ribbon slack between the spool and the ribbon controlled means.

13. In a typewriter or the like, a pair of ribbon spools to which a ribbon is adapted to be connected, a shaft for each spool consisting of upper and lower sections rotatable relatively one to the other, the spool being fixed to the upper shaft section, means for feeding said ribbon from one spool to the other, means for rotating said shaft sections in the same direction under the influence of the ribbon feeding means, a ribbon reversing mechanism associated with each spool, said upper shaft section being provided with a series of ratchet teeth, a ribbon-controlled means for operating said reversing mechanism, means for returning the ribbon-controlled means to its initial position whereby a slack in the ribbon will be formed between the spool and the ribbon-controlled means, and means movable with the ribbon-controlled means and operable during the return movement of the latter to engage the ratchet teeth and thereby rotate the upper shaft section in the same direction as the lower shaft section to take up said ribbon slack, said upper shaft section being rotated by the ribbon-controlled means independently of the ribbon feeding means.

In testimony whereof, I have hereunto subscribed my name.

GEORGE F. HANDLEY.
